UNITED STATES PATENT OFFICE

133,903

DESIGN FOR A SHOE

Charles Tweedie, Jefferson City, Mo.

Application December 26, 1941, Serial No. 104,861

Term of patent 14 years

To all whom it may concern:

Be it known that I, Charles Tweedie, a citizen of the United States and a resident of Jefferson City, in the county of Cole and State of Missouri, have invented a new, original, and ornamental Design for a Shoe, of which the following is a specification, reference being had to the accompanying drawing, forming part thereof.

Fig. 1 is a perspective view of a shoe showing my new design, the essential features of which are shown in full lines, and the opposite side presenting substantially the same appearance as the side shown;

Fig. 2 is an enlarged fragmentary view of the shoe so as to bring out more clearly the details of the ornamentation.

In the drawing, the lining of the top line por-

tion does not indicate any particular color. The specific disclosure is of a leather shoe body and an elastic goring fabric arranged in edgewise abutting relation and joined by stitching in the form of three longitudinal zigzags arranged to form two longitudinal series of diamonds with two sides of every diamond common to adjacent diamonds and while my design is shown as applied around the throat of a step-in pump style of a shoe it is contemplated that the design may be similarly applied to other styles of shoes without departing from the spirit of the invention.

I claim:

The ornamental design for a shoe, as shown and described.

CHARLES TWEEDIE.
